WEATHER AND CARPET STRIP

Laurence E. Voorhees, Washington, D. C.

Application May 10, 1937, Serial No. 141,832

4 Claims. (Cl. 20—68)

My invention relates to weather strips and carpet strips applicable to closures, and particularly to the type closing the entire space between the lower edge of a door and its threshold.

5 One object of my invention is to improve the type of weather and carpet strip which comprises a housing positioned at the lower portion of a door, and a slideable member capable of being projected out of the housing to close and seal the 10 entire space between the lower portion of the door and its threshold when the door is closed, and capable of being retracted into the housing when the door is opened in order to enable the lower edge of the door to clear rugs, carpets, etc., 15 disposed between the floor and the door.

Another object of my invention is to provide a 20 weather strip with telescoping side walls, and a horizontal cross section substantially identical with the horizontal cross section of the lower marginal portion of the closure with which it 25 coacts to vary the distance between the closure and its threshold, without detracting from the artistic design and aesthetic appearance of the closure and its surrounding structure.

25 Another object of the invention resides in providing a release spring coacting with the mechanism which operates the retractable drop member of the weather strip, said spring being sufficiently stiff to insure the depression of said drop 30 member into its position snugly contacting the threshold, and yet sufficiently resilient so as to safeguard the mechanism against injury should the downward motion of said drop be obstructed in any way as would be the case if some object 35 was positioned between the drop and the threshold or the distance between the drop and its threshold changed.

An important feature of this invention resides 40 in that part of the weather strip operating mechanism which coacts with the jamb of the framework to which a closure is hinged, when the closure approaches its closed position. Said part comprises a plunger with a rotatable head contacting the curved surface of a plate mounted 45 in said jamb, the curvature of the surface of said plate being such that the axis of the plunger is always perpendicular to the surface of the plate at the point of contact of the plunger's rotatable head, which results in a smooth and frictionless 50 application of the force which operates the weather strip as the closure is brought to its closed position.

Another important feature of the invention 55 resides in a pantographically arranged linkage device pivotally attached to and cooperating with

the housing member, sealing drop member and the linkage device operating member which coacts with the closure frame, for rapidly projecting the sealing drop member out of the housing member when the closure approaches its closed position within its frame.

A further object of the invention resides in the construction and positioning of the springs which support the retractable drop member in such a manner as to cause the end of said member nearest to the hinge of the closure to move toward the threshold first as the closure is brought to its closed position, and to rise from the threshold last as the closure is opened, thus enabling the lower edge of the closure farthest from its hinged support to clear rugs or carpet abutting the threshold immediately below the closure when in its closed position.

A still further object of the invention is to provide a simple, substantial and economical 20 weather and carpet strip that will not mar the beauty of any building closure, and that may be installed on the closure by an unskilled person with ordinary tools and without requiring special and expensive millwork on the closure before installation of the weather strip.

Other novel features of my invention from a practical standpoint will be apparent as herein-after illustrated and/or described.

In the drawing wherein like numerals represent like parts:

Fig. 1 is a perspective view of a portion of a swinging door type closure and its supporting framework showing the application of my invention thereto, and particularly the manner in 35 which the plunger member coacts with the curved plate mounted on the door frame jamb.

Fig. 2 is a fragmentary plan view of the preferred form of my invention with the web of the housing cut away in order to permit a top view 40 of the interior of the weather strip.

Fig. 3 is a fragmentary elevational view of the preferred form of my invention with one side of the housing and the retractable member cut away in order to permit a side view of the interior of 45 the weather strip.

Fig. 4 is a fragmentary cross sectional view of the door and its associated framework jamb taken on line I—I of Fig. 1, except that the door is approaching its closed position illustrating in 50 detail the coaction between the plunger member and the curved plate mounted on the jamb of the door frame.

Fig. 5 is a fragmentary elevational view of the front edge of a door equipped with the preferred 55

form of my invention which shows the retractable drop member in its operated extended position in contact with the door sill, and

Fig. 6 is a fragmentary cross sectional view of 5 a door equipped with a form of my invention in which the flanges of the channel-shaped housing are formed by the comparatively thin sheet material of which the lower marginal portion of the door is constructed, with the web member of 10 the housing removably attached to said flange members. This figure also shows the retractable drop member in its completely retracted position within the housing.

In Figs. 1 to 5 inclusive, numeral 10 represents 15 the common door type of closure fragmentarily illustrated. The lower marginal portion of the door is designated by numeral 11. The rear hinged edge of the door is designated by numeral 12. The front edge of the door is designated by 20 numeral 13. The lower edge of the door is designated by numeral 14. The rear edge 12 of the door is mounted to jamb 15 of the framework 16 by hinges, one of which is designated by 25 numeral 17. The door swings over the floor 18 and the sill 19. The type of weather and carpet strip described herein is employed to close the entire space between the lower edge 14 of the door 10 and the sill or threshold 19 when the door is closed in its framework 16, and to leave sufficient space 30 between its lower edge 14 and the floor 18 over which it swings to clear rugs, carpets, etc., disposed on the floor 18.

This form of my invention consists of a weather and carpet strip represented in its entirety by 35 numeral 20. The entire structure 20 is constructed as a self contained unit which is removably attached to the lower edge 14 of the door 10 and comprises a housing 21 and a retractable sealing member or drop 22 which movably telescopes within said housing in its retracted 40 position and is capable of being projected out of said housing to contact its threshold or sill 19 and entirely and completely close the space between the lower edge of the door and the sill or floor as the case may be. My invention operates in effect to extend the lower marginal portion 45 of the door 10 downwardly to meet the threshold or sill 19.

The housing 21 is constructed from sheet metal 50 or other suitable material formed in the shape of an elongated channel with a U-shaped cross section. The side walls or flanges 23 and 24 of the housing are parallel and spaced apart so that their outer surfaces are flush with the sides 55 of the lower marginal portion 11 of the door 10. A web 25 connects the upper edges of the side walls 23 and 24 and forms an integral part thereof. Side walls 23 and 24 are perpendicular to web 25. The upper outside edges 26 and 27 60 of the housing are sharply formed so that the side walls 23 and 24 are absolutely flush with the sides of the lower marginal portion 11 of the door with no indenture whatever at the junction line 65 28. The ends of the housing 21 are enclosed by two parallel end walls 29 and 30 formed by bending projections of the web 25 downwardly and welding or otherwise securing the edges of the end walls formed thereby to the edges of the side walls 23 and 24 at 31, 32, 33 and 34. End walls 70 29 and 30 are perpendicular to web 25. Web 25 has holes 35 formed therein through which screws 36 are driven into the lower edge 14 of the door to secure the weatherstrip to the door.

The retractable member or drop 22 is also 75 constructed from sheet metal or other suitable

material formed in the shape of an elongated channel with a U-shaped cross section. The side walls or flanges 37 and 38 of the retractable drop member are parallel and have their lower edges connected by a web 39 which forms an integral 5 part thereof. Side walls 37 and 38 are perpendicular to web 39. The ends of the drop member 22 are enclosed by two parallel end walls 40 and 41 formed by bending projections of the web 39 upwardly and welding or otherwise securing the edges of the end walls formed thereby to the edges of the side walls 37 and 38 at 42, 43, 44 and 45. End walls 40 and 41 are perpendicular to web 39. The side walls 37 and 38, and the end walls 40 and 41 of the drop 22 are spaced apart 10 so that the drop freely telescopes within the housing 21. Web 39 has holes 46 formed therein directly beneath the holes 35 formed in web 25 of housing 21 so that a screw-driver may be inserted through holes 46 and engage screws 36. 15 A sealing strip 47 constructed of rubber impregnated canvas, felt or other suitable material is fastened to the lower surface of web 39 by means of metal screws 48 so that the sealing strip may be removed to permit the insertion of a screw-driver through holes 46 when attaching the weather strip to the door. Tongues 49 are struck from web 39 and are disposed at right angles to web 39. Tongues 49 fit freely into recesses in the ends of rods 50, said rods being 20 pivoted to tongues 49 by means of cotter pins 51 which pass through holes in the rods and tongues. Rods 50 extend upwardly through holes 52 in web 25. Washers 53 are disposed at the upper 25 ends of rods 50 and are held in place by cotter pins 54 passing through holes in the upper ends of rods 50. Compression springs 55 are disposed around rods 50 and between washers 53 and web 25. The retractable drop member 22 is continually urged upwardly into housing 21 by springs 40 55, and when the drop 22 is telescoped into housing 21 as far as it can go, its lower sealing surface is flush with the lower edges of walls 23, 24, 29 and 30 of housing 21.

Bearing plates 56 and 57 are constructed of 45 sheet metal formed with a U-shaped cross section. Web 58 of bearing plate 56 is rigidly attached to web 25 of housing 21 by means of rivets 59, or other suitable means, at a point approximately midway between end walls 29 and 30 of housing 21. Web 60 of bearing plate 57 contacts web 39 of drop 22. Flanges 61 and 62 of bearing plate 56 and flanges 63 and 64 of bearing plate 57 have bearings 65 and 66 formed at 50 their midpoints the axes of said bearings running substantially at right angles to the housing walls 23 and 24. Holes 67 and 68 are struck in the centers of webs 58 and 60 respectively. Tubular member 69 is collapsed at one end to form a flat portion 70 which has bearing 71 and slot 72 55 formed therein. Links 73 are constructed from sheet metal and connect the bearing points 65, 66, 71 and 74, forming a pantographic configuration. Bearing 74 slides freely in slot 72. Rivets 60 form the pivotal member at the bearing points 65, 66, 71 and 74. Groove 75 is formed in the flat portion 70 of the tubular member 69, said groove 65 engaging the rivet at bearing 65. The purpose of groove 75 and holes 67 and 68 is to provide a minimum distance between webs 56 and 57 when the pantographic linkage device is collapsed. By 70 means of this pantographic linkage device, longitudinal displacement of tubular member 69 is translated into vertical displacement of bearing plate 56 with respect to bearing plate 57. With 75

bearing plate 56 rigidly attached to web 25 of the housing 21 and bearing plate 57 contacting web 39 of drop 22, any downward movement of bearing plate 57 with respect to bearing plate 56 projects the drop 22 out of the housing 21 against the action of springs 55. Rod 76 is freely slideable within tubular member 69. The end of the tubular member 69 is positioned adjacent to the inner side of wall 41 of drop 22 when the drop is in its fully retracted position. Rod 76 has a pin 77 positioned at right angles to its axis, said pin extending through slots 78 located diametrically opposite each other and formed in the walls of tubular member 69. Pin 77 is freely slideable in slots 78. Spring 79 is disposed in the tubular member 69 between the end of rod 76 and rivet 80 positioned diametrically across tubular member 69. Spring 79 operates only when the downward movement of drop 22 is stopped. Rod 76 passes through guide hole 81 in end wall 30 of housing 21. End wall 41 of drop 22 has a groove at 82 formed in its upper edge, said groove engaging rod 76 when drop 22 is fully retracted into housing 21. Roller 83 is disposed in a slot formed in the end of rod 76 which is outside of the housing 21, said roller being rotatable on pin 84 positioned through the sides of the slot.

The spring 55, which is positioned between the rear edge 12 of door 10 and the pantographic device, is nearer to the pantographic device than is the spring 55 which is positioned between the front edge 13 of the door 10 and the pantographic device. The purpose of this unequal spacing of springs 55 with respect to the pantographic device is to cause the end of the drop 22 nearest the rear edge 12 of the door 10 to be projected first and retracted last.

A metal plate 85 is attached to door frame jamb 15 by means of screws 86 and positioned so as to contact the roller 83 disposed on the end of rod 76 when the door 10 is brought to its closed position. The contacting surface of plate 85 is curved so that the axes AB of rod 76 is always at right angles to the tangent CD at the point of contact 95 of the curved surface of plate 85 with the roller 83. Roller 83 permits the end of rod 76 to travel freely along the surface of plate 85 as the door 10 is being brought to its closed position. In this way the force employed to operate the weather strip mechanism is substantially applied in the direction of and along the axis of rod 76 with no substantial components of the force acting at right angles to the axis of the rod 76.

Fig. 6 shows a method of forming the housing of my invention where the door or closure is constructed of sheet metal instead of solid wood. The side and front-edge walls of the lower portion of the door form the side and front-end walls respectively of the housing of the weather strip. In Fig. 6, 87 and 88 represent the side walls of the weather strip housing 89. The lower portion of the door is represented by numeral 90. Numeral 91 represents the web of the channel-shaped housing 89, web 91 having a portion bent downwardly to form the rear-end wall of the housing 89. Web 91 is fastened to brackets 92 by means of screws 93, said brackets being disposed at spaced points along the sides 87 and 88 and rigidly attached to said sides by welding or other means. The front vertical edges of sides 87 and 88 are integrally connected by welding or otherwise to the vertical edges of the front-end wall of the housing 89. The rear vertical edges of the side walls 87 and 88 are formed around the rear-end wall of housing 89 and removably

attached thereto. Drop 22 telescopes into housing 89 in the same manner as it did into housing 21 designed to be attached to wood doors.

The weather and carpet strip illustrated in Figs. 1 to 5 inclusive is a completely assembled unit with the exception of the sealing member 47 which is fastened in place after the unit is attached to the wood door.

To mount the weather strip unit the lower portion 11 of the door must be sawed off so that with the unit in place and the drop 22 fully retracted within housing 21, the lower surface of the sealing strip 47 of the drop 22 will easily clear any rugs or carpet disposed on the floor over which the door swings. Holes 94 are then drilled in the lower marginal portion 11 of the door to provide space for springs 55. The housing 21 is then attached to the lower edge 14 of the door by means of screws, access to said screws being provided through holes 46 in web 39 of drop 22. After the weather strip has been mounted on the door, the sealing strip 47 is fastened in place by means of screws 48. Plate 85 is fastened to jamb 15 of the door frame 16 by means of screws 86 in a position so as to contact roller 83 of rod 76 as shown in Fig. 4.

In weather strip units for use with metal doors of the type illustrated in Fig. 6, the assembled unit is the same as that employed on wood doors except that web 91, which has a portion bent downwardly to form the rear-end wall of the housing 89, is the only part of housing 89 which forms a part of the assembled unit. No drillings for holes to accommodate springs 55 are required for metal doors since the springs merely extend into the free space within the lower portion 90 of the metal door.

The operation of my invention is as follows: Let us start with the door 10 in the open position with respect to door frame 16. As door 10 is brought toward its closed position, roller 83 contacts the curved surface of plate 85 just about the time the rear edge 12 of door 10 is beginning to swing over sill 19. The pressure of roller 83 against plate 85 causes rod 76 to move forwardly. Since spring 79 is very stiff, the motion of rod 76 is transferred to tubular member 69 without compressing spring 79. The forward motion of tubular member 69 is translated by the pantographic linkage device into vertical downward motion of bearing plate 57 with respect to bearing plate 56. Bearing plate 57 presses against web 39 of drop 22 forcing drop 22 downwardly, thereby compressing springs 55. The unequal spacing of springs 55 from the pantographic device causes the rear end of drop 22 to proceed downwardly before the front end of drop 22 and contact sill 19. In this manner the front end of drop 22 is allowed to be raised so as to clear carpets or rugs disposed on the floor 18 over which the door 10 swings as long as the front edge 13 of door 10 is over the floor 18 and not over sill 19. From the time the rear edge 12 of door 10 starts swinging over sill 19 until the front edge 13 is entirely over sill 19, drop 22 is being projected downwardly at an angle whose apex is the contact point of the rear end of drop 22 and the sill 19. When door 10 is completely closed the entire sealing surface of sealing strip 47 is in contact with the surface of sill 19, and this is true even if the lower edge 14 of door 10 is not parallel to the upper surface of the sill 19. When the sealing strip 47 of drop 22 is fully in contact with sill 19 and drop 22 cannot move downwardly any further, spring 79 is compressed

by further forward motion of rod 16, thereby providing a safety release feature and at the same time maintaining a sealing pressure between sealing strip 47 and sill 19. This safety release feature is important in case some foreign object becomes disposed between the sill 19 and the drop 22, and also eliminates the necessity for adjusting the weather strip for variations in the included space between the lower edges of the side walls 23, 24, 29, and 30 of the housing 21 and the sill 19 due to shrinkage of the wood member of the closure, or settling of the threshold. When door 10 is opened, rod 16 moves rearwardly allowing springs 55 to expand and retract drop 22 into housing 21. The front end of drop 22 is drawn upwardly before the rear end of drop 22.

The construction of my invention prevents water and dirt from getting into the operating parts and obstructing their smooth operation.

Changes in the specific form of my invention, as herein disclosed, may be made within the scope of the subjoined claims without departing from the spirit of my invention.

Having described my invention, I claim:

1. The combination with a door frame and a door hinged at one edge thereof to said frame, of a weather and carpet strip positioned below the lower marginal portion of said door for closing substantially the entire space between the lower edge of the door and its subjacent threshold, said weather and carpet strip comprising an elongated channel-shaped housing having a web removably attached to the lower edge of the lower marginal portion of said door and upwardly disposed with respect to flanges perpendicular to said web and spaced so as to be flush with corresponding faces of the door, an elongated channel-shaped sealing drop having a web downwardly disposed with respect to flanges perpendicular to said web and spaced so as to permit the drop to freely telescope into projected and retracted positions within said housing, means for projecting the sealing drop out of the housing when the door is closed and thereby bringing the lower sealing strip thereof into yielding engagement with its subjacent threshold, and means for retracting the sealing drop within the housing when the door is opened.

2. In a weather strip attached to a marginal portion of a closure movable relative to a frame, said weather strip closing the space between said marginal portion of the closure and the corresponding adjacent portion of said frame in the closed position of the closure, the combination of those parts consisting of a rotatable bearing positioned in the contacting portion of the operating member cooperating with the said weather strip mechanism and the closure frame, and a contact member mounted on the closure frame, said

contact member having a curved contact surface cooperating with the rotatable bearing on the said operating member so that the lengthwise axis of said operating member is substantially perpendicular to the tangent to the curved contact surface at the point of contact with the rotatable bearing for all positions of the closure while contact is established between the contact member and the rotatable bearing.

3. In a weather and carpet strip attached to a marginal portion of a closure movable relative to a frame, said weather strip closing the space between said marginal portion of the closure and the corresponding adjacent portion of said frame in the closed position of the closure and comprising a housing, a sealing drop capable of telescoping freely into projected and retracted positions within said housing, and an operating member coacting with the closure frame, that part comprising four links, each link having a plurality of rigid members, said links arranged in pantographic form with their ends pivotally joined, two opposite joints pivotally attached to the said housing and sealing drop respectively, a third joint pivotally attached to said operating member, and the pivot of the fourth joint, opposite the third joint, movable in a slot formed in the operating member parallel to the lengthwise axis thereof, said pantographic linkage device rapidly projecting the sealing drop straight out of its housing when the closure approaches its closed position in its frame.

4. The combination with a frame and a closure movable relative to said frame, of a weather strip for closing substantially the entire space between the marginal portion of said closure and the corresponding adjacent portion of said frame in the closed position of said closure, said weather strip comprising an elongated channel-shaped housing removably attached to the marginal portion of said closure, having a web inwardly disposed with respect to flanges perpendicular to said web, said flanges spaced apart so that their surfaces are flush with the corresponding adjacent surfaces of the sides of the marginal portion of said closure, an elongated channel-shaped sealing member having a web outwardly disposed with respect to flanges perpendicular to said web, said flanges spaced apart and positioned adjacent to the flanges of said housing so as to permit said sealing member to freely telescope into projected and retracted positions within said housing, means for projecting the sealing member out of the housing when the closure is closed and thereby bringing said sealing member into yielding engagement with its adjacent threshold, and means for retracting the sealing member into the housing when the closure is opened.

LAURENCE E. VOORHEES. 60
